(57) **CLAIM**

The ornamental design for a glow-in-the-dark pacifier set, as shown and described.

DESCRIPTION

FIG. 1 is a perspective view of a glow-in-the-dark pacifier, showing my new design of one handle in the set;

FIG. 2 is a top view thereof;

FIG. 3 is a side view thereof, the opposite side being a mirror image;

FIG. 4 is a bottom view thereof;

FIG. 5 is a front view thereof; and,

FIG. 6 is a front view of alternate embodiments of the handle portion depicted in FIG. 1 of the pacifier set.
